PANEL ILLUMINATION

Martin J. Caserio and Henry C. Stuerzl, Flint, Mich., assignors to General Motors Corporation, Detroit, Mich., a corporation of Delaware

Application June 27, 1955, Serial No. 518,018

5 Claims. (Cl. 40—132)

This invention relates to illuminating means and more particularly to means for illuminating a transparent or luminescent panel. In many instances, such for example as in advertising signs or instrument panels, flat panels bearing indicia, lettering, or scales must be furnished with illumination. Various means have been used in the past to provide illumination for such configurations or indicia which include fluorescent means irradiated or activated by an external source of light, so-called edge lighting, or other indirect lighting schemes.

More recently a different type of lighting has been introduced which may be defined as an electro-luminescent lamp. These lamps consist of laminated sheets of material which when energized produce a glow over the whole surface to illuminate the surroundings. Such a lighting means is disclosed in United States Patent to Eric L. Mager 2,566,349, issued September 4, 1951. In this form a glass or other transparent plate is provided upon one face of which is secured a thin sheet of tin chloride which is electrically conductive and transparent. Next in laminated assembly is a sheet of fluorescent phosphor which is electrically insulating and which is lastly covered with a sheet of aluminum also acting as an electrical conductor. As stated in the above mentioned Mager patent in column 1 beginning at line 9: "In the electroluminescent lamp the light appears to be produced only when the voltage is applied and when it is removed, or when the voltage is changed. Such lamps are accordingly most effective when used on alternating, pulsating or otherwise varying currents." Thus, where an alternating electric voltage of the proper cycle and of the proper value is applied to the sheets of tin chloride and aluminum, a continuously variable electrical field is set up between the two which causes the intermediate fluorescent phosphor sheet to glow. Since the tin chloride sheet is transparent, the glow is visible through the glass and the whole panel appears to be illuminated. Such type of illumination is, however, plain and even over the surface. This does not provide for the illumination of any scales or indicia such as would be necessary in instrument panels or in advertising signs of various types.

It is therefore an object in making this invention to provide panel illumination incorporating desired configurations such as indicia for use in instrumentation or advertising.

It is a further object in making this invention to provide laminar construction incorporating both configuration and illuminating features therein.

It is a still further object in making this invention to provide illuminating means having built-in configurations.

With these and other objects in view which will become apparent as the specification proceeds, our invention will be best understood by reference to the following specification and claims and the illustrations in the accompanying drawings, in which:

Figure 1 is a plan view of one element of an instrument panel cluster incorporating the features of our invention.

2

Figure 2 is an enlarged sectional view taken on the line 2—2 of Figure 1.

Figure 3 is an exploded view of the components of our laminated structure to show their relative positions; and

Figure 4 is a cross section showing the elements in spaced relation of a modified form of our invention.

Referring now more particularly to Figures 1 and 2, there is shown therein, as an example only, a speedometer dial 2 which is used with automotive vehicles. The dial plate is supported in a framework 4 and an indicating pointer 6 is adapted to move across the dial to indicate the vehicle speed. The dial itself is best shown in the section Figure 2. It consists of several plates of differing materials laminated together and the assembly is mounted

in a supporting bracket 8. This assembly consists, and reference is herein made to Figure 3 as clearly showing the components, of a front plate 10 which is transparent and may, for example, be formed of glass or plastic. The next sheet 12 is formed of tin chloride which has two characteristics which are useful: one, it is electrically conductive, and two, it is substantially transparent. This sheet necessarily is relatively thin.

In order to obtain some means to provide intelligence, the next layer consists of figures or configurations of the desired forms. In this example these would take the shape of numerals 14 which are placed on the surface of the tin chloride sheet 12 at desired locations in order to obtain the proper pattern. These numerals are formed

from a sheet of fluorescent phosphor. These numerals may also be printed, silk screened, or painted on fluorescent phosphor material on the surface of the tin chloride sheet 12 if desired. After the numerals 14 are properly secured to the surface of the tin chloride sheet 12, a sheet

16 or layer of non-electrically conducting or insulating material is then applied. This can be of almost any type and may, for example, be a layer of non-conducting paint. If paint is used it may be colored to give the desired aesthetic effect to the panel. Lastly, a sheet 18 of aluminum or other similar material is applied, which is, of course, electrically conductive, and which will be insulated from sheet 12 by both the fluorescent phosphor and insulating sheet 16. These members are laminated together by any desired means which holds them in juxtaposition.

When they are in position, alternating current electrical power is applied to the tin chloride sheet 12 and the aluminum sheet 18 through power lines 20 and 22. The application of power to these two surfaces creates an electrical field between the two, which field causes the fluorescent phosphor layer to glow. In this instance this layer consists of numerals and these numerals glow. They are visible through the front of the assembly and appear to be unsupported in space. Therefore, when such laminar assembly is supported in the bracket 8 and electric power applied, it produces a very satisfactory night illumination for such a device as a speedometer of an automobile.

In some instances it may be desirable to not only illuminate the configurations supported in a laminar panel as above described, but also to illuminate other devices in the area. Again using as an example the speedometer

panel of an automotive vehicle, it might be desirable to illuminate the cavity behind the instrument panel to provide illumination for the cigarette lighter so that it may be easily found. Figure 4 therefore shows a modified form of our invention which includes not only configuration illumination but also an area of the panel for projecting rays in the opposite direction for any desired use. Referring more particularly to Figure 4, the same reference numerals will be applied to similar members and the

assembly consists of a front plate 10 which may be of glass, a second layer 12 of tin chloride, which is thin and transparent and electrically conductive. An indicia or

3

configuration layer, in this instance 14', is shown as extending over most of the surface of the panel or may be applied in specific areas as needed; and is, therefore, of a different type than that shown in Figures 1 through 3. The third layer 16 of insulating material such, for example, as paint, is provided, and lastly the sheet 18 of aluminum which is used as an electrical conductor and final laminar sheet. The assembly so far described as in the previous instance not only illuminates the indicia laminated therein but provides a certain amount of illumination radiating from the front face as indicated by the arrows.

If it is desired to also have some illumination radiating to the rear to illuminate other parts, such as gages, speedometer pointers, etc., this is provided by duplicating similar structure on the rear face of aluminum sheet 18, utilizing that sheet as a common sheet of both sections of illumination. While it would be perfectly plausible to make the size sheet on the rear face of exactly the same size as the front, it can also be made any partial size as desired and in this example is only of a relatively small size. The first part to be laminated to the lower rear surface of the sheet 18 is a sheet of fluorescent phosphor 24. This sheet 24 in this instance is shown as a complete layer since it is only desired to obtain radiated illumination in this direction and not any particular laminated configuration or indicia illumination. The fluorescent phosphor layer 24 is therefore of the same size as the next in order tin chloride sheet 26 and acts as an electrical insulator between that sheet and sheet 18. Lastly in order is a transparent or glass sheet 28 which completes the smaller laminar assembly on the back face of aluminum conductor sheet 18.

When electrical power is applied across power lines 20 and 22 in Figure 4, the configurations in the sheet 14' are illuminated. By then connecting input line 20 through tie line 30 with the tin chloride sheet 26, a similar field is set up in the rear laminar section between plates 26 and aluminum conductor 18. In this instance, however, the fluorescent phosphor sheet 24 will glow evenly over the whole area producing rays of illumination to the rear to be used for any desired purpose. Figure 4, therefore, shows a combination system for illuminating indicia or desired configurations and at the same time providing external illumination in another direction for any desired associated pieces of equipment. If it is desired to view a pointer such as 6 through the panel instead of having the pointer move in front of the panel, a clear section or window may be provided by omitting an area of insulating material 16 and a like area of the conductive sheet 18. This will provide a transparent area in the panel and parts on the opposite side of the panel may be viewed therethrough without affecting the operation of the rest of the panel.

We claim:

1. In illuminating means, a thin transparent electrically conductive sheet, electro-luminescent phosphor means having a desired configuration secured to one side of said conductive sheet, an electrically insulating layer secured to that side of the sheet and covering the configurations and a second sheet of electrically conductive material secured adjacent the electrically insulating layer to produce

4

a variable field between the two conductive sheets when voltage is applied thereacross to cause the electro-luminescent phosphor means to glow to produce indicating material.

5 2. In illuminating means, a laminar assembly formed of a sheet of aluminum, a layer of electrical insulating colored material, a section of electro-luminescent material cut to a desired configuration to provide intelligence, a sheet of tin chloride which is transparent and a layer of transparent material so that upon application of alternating current electrical power to the aluminum and tin chloride sheets a variable field will be set up between them to cause the electro-luminescent material to radiate which is visible through the tin chloride sheet and transparent panel with a colored background.

10 3. In illuminating means, a first member of electrically conductive material, a plurality of second members of electrically conductive material mounted in insulated relation on each side of said first member, electro-luminescent means interposed between the first and each second member to radiate when a potential is applied to the first and second members, at least one of the electro-luminescent means being formed in a configuration to convey intelligence and the other to provide general illumination.

15 4. In illuminating means, a first member of electrically conductive material, a plurality of second members of electrically conductive material mounted in insulated relation on each side of said first member, electro-luminescent means interposed between the first and each second member to radiate when a potential is applied to the first and second members, at least one of the electro-luminescent means being formed in a configuration to convey intelligence, and said second members being sufficiently thin to be transparent to the passage of light rays.

20 5. In illuminating means, a member of electrically conductive material, a layer of insulating material supported over one face of the member, electro-luminescent means cut in a desired configuration and affixed to said insulating layer, a sheet of transparent, electrically conductive material mounted over the electro-luminescent means and means to apply a potential to the member of electrically conductive material and the transparent sheet of electrically conductive material to develop a variable field between the two to cause the electro-luminescent means to glow, a sheet of electro-luminescent material secured to the opposite face of the first-named member of electrically conductive material, a second sheet of transparent electrically conductive material secured to the sheet of electro-luminescent material and electrically connected to the first transparent sheet to provide a variable electric field on the opposite side of the first-named member also to provide general illumination.
